UNITED STATES PATENT OFFICE.

ALBERT LATHAM, DECEASED, LATE OF BEVERLY, MASSACHUSETTS, BY JAMES W. NOURBOURN, OF SOMERVILLE, MASSACHUSETTS, ADMINISTRATOR, ASSIGNOR TO AMERICAN BUTTON & FASTENER CO., OF AUGUSTA, MAINE, A CORPORATION OF MAINE.

SUPPLYING APPARATUS.

Original application filed June 26, 1920, Serial No. 391,908. Divided and this application filed August 4, 1925. Serial No. 48,084.

This invention relates to apparatus for supplying various objects to machines for operating upon them, it being of particular utility as applied to the feeding of buttons to such an attaching machine as that described in the application for Letters Patent of the United States filed in the name of Albert Latham, on June 26, 1920, and bearing the Serial Number 391,908, of which 10 the present application is a division.

An object of the invention is to effect delivery of the articles in a positive and regular manner, assuring an unfailing supply at the machine fed. This end is attained by 15 combining in a novel manner with an object-container a receiver, from which may lead a raceway or other conveyor for objects, there being means between which and the container there is a relative movement serving to deliver objects from the container to the receiver and from the receiver to the conveyor. The delivering means, which may be furnished by one or more carriers, is preferably arranged to engage individual 20 objects and to move in the container, as through the bottom thereof, the carriers being shown as pins operating in openings in the container-bottom, and adapted to enter button-eyes. Associated with the carriers may be means for positioning the objects upon them in preparation for their delivery. As disclosed, there is provided 25 means for raising the pins to engage the objects, and means for imparting to them a compound lateral movement to carry the objects outwardly and turn them upon the pins so that they will be ready for delivery. Obviously, in certain aspects of the invention, it is immaterial whether or not there 30 be a receiver independent of the associated elements.

In the accompanying drawings, a particular embodiment of the invention is illustrated in connection with a portion of the machine of the application above mentioned, which is for attaching buttons by means of staples passed through the eyes.

In Fig. 1, the supplying apparatus, to-

gether with the associated attaching machine, appears in partial side elevation; 50

Fig. 2 is a detail in side elevation of the adjusting means for the guideway or receiver;

Fig. 3 shows the supplying apparatus in 55 sectional perspective;

Fig. 4 is a central vertical section through said apparatus; and

Fig. 5 is an enlarged sectional detail taken through one side of the supplying apparatus. 60

A frame 10, which may carry setting mechanism 11 and controlling mechanism 12 for the fastenings to be attached, together with the actuating means therefor, supports a raceway 13 for the feeding or supplying mechanism of the present invention, this last-mentioned mechanism delivering buttons to the controlling mechanism. A raceway 14 is also illustrated for staples to be delivered to the controlling mechanism for 65 association with the buttons which they are to secure. The setting, controlling and staple-feeding mechanisms will not be further considered, not being essential to this invention. 70

The button-raceway includes an inclined slot 30 extending laterally in a horizontal direction and serving to receive the button-eyes, while a groove 32 formed just below this cooperates with the heads of the buttons. One wall of the groove 32 is furnished by an extended depression in the frame, while the opposite wall is provided by a plate 34 attached to the frame by screws 36 passing through vertical slots 38 80 in the plate. The slotted connection of the plate to the frame permits the vertical adjustment of the former, thereby changing the relation between the head-groove and the eye-slot, so that the buttons may rest 85 properly therein to travel down the raceway without clogging. 90

The raceway 13 is supplied with buttons from a hopper 42 attached to one side of the upper portion of the frame, and having an 95 inclined bottom-wall delivering through a

throat 44 into a cylindrical receptacle or container 46. Surrounding the upper portion of the container and joined to the upper end of the button-raceway 13 is a receiver or guideway 48, the inner wall of which is furnished by the reduced upper edge 50 of the container. The outer wall may consist of a cylindrical casing 52 curved inwardly at 54 over a shoulder at the top 10 of the container into proximity with the wall 50. There is thus formed an annular groove in which the button-heads will rest for movement with relatively slight friction, and with the button-eyes overlying the 15 top of the edge 50. To so arrange this eye-engaging edge of the groove that the buttons may be supported to the best advantage for their travel along the raceway, the depth of the groove may be varied by raising or 20 lowering the casing by means of a screw 56 (Fig. 2) threaded through a lug 58 projecting outwardly from the top of the casing and contacting with a bracket 60 formed upon the frame. To guide the casing in its 25 movement of adjustment, there is provided a pin 62 rising from the top of the bracket and extending through an opening in the lug 58. Obviously, if buttons with heads of small diameter are to be fed, the casing 30 will be raised so that the bottom of the groove will lie nearer the top of the edge 50 than if the heads are of greater diameter.

To transfer buttons from the mass in the container to the receiver, elevating or carrier members in the form of pins 64 are movable through a circular series of openings 66 in the outer portion of the bottom of the container, toward which openings this bottom-wall is inclined at 68. The pins are 35 respectively fixed to the upwardly extending arms of a corresponding series of bell-crank levers 70 having pivot pins 72 movable through pairs of radial, horizontal slots 74 near the periphery of a supporting member 45 or head 76. This head is fixed upon the lower extremity of a vertical rod 78 passing through the bottom of the container, and carried by an arm 80 secured at the upper end of a bar 82 arranged to reciprocate vertically in ways in the frame. The bar contains in its lower portion a transverse opening 84 to receive the rounded end of a lever 86 pivoted at 88 upon the frame. Articulated to this lever is a link 90 turning upon 50 the pin of a crank-disk 92 carried upon the end of a short shaft 94 journaled transversely at the bottom of the frame. This shaft is connected by spiral-gearing 96 with a longitudinal shaft 98, which, in turn, is 55 united through spur-gearing 100 with the actuating mechanism of the machine, which mechanism may include a single-rotation clutch rotated from any suitable source of power and not herein illustrated. As the 60 crank-disk 92 turns, it oscillates the lever 86

and reciprocates the bar 82, thus raising and lowering the head 76. Raising the head causes the pins 64 to be carried upwardly from their normal position illustrated in Fig. 3 of the drawings, in which the reduced 70 points are just below the tops of the openings 66 in the bottom of the container, to the positions appearing in Figs. 4 and 5, in which said points are above the upper edge of the wall 50. In thus rising, a certain 75 number of the pins will enter the eyes of buttons lying in a body in the bottom of the container, and elevate them to points above the receiving groove 48. Each of the bell-cranks 70 has a horizontal arm rounded 80 at 112, this portion of the lever being pressed by a spring 114, located in a horizontal recess 116 in the head, against the smooth interior surface of a sleeve 118 movable vertically within a downward cylindrical extension 120 of the container. The travel of this sleeve from the container is limited by a flanged ring 122 screwed upon the bottom of the extension 120; while its upward movement is arrested by a pin 124 depending from 85 the bottom of the container. Formed at the inner top portion of the sleeve 118 is an annular cam 126 having a lower inclined surface 128 and above this a depression 130. As the head is raised and the bell-crank 90 levers 70 approach the top of the sleeve 118, which is now resting upon the ring 122, the ends 112 of the levers ride over the surface 128, and are by this contact swung outwardly so that they are shifted from their 95 normal vertical position to the inclined relation shown in Fig. 4 of the drawings, in which the points are above the button-receiving groove 48. The frictional engagement of the levers with the cam raises the 100 sleeve with the head until the former is stopped by contact with the pin 124. In this travel, the levers pass over an elevation or ridge 131 between the surface 128 and the depression 130, and snap sharply into said 105 depression under the influence of the springs 114, this movement being more rapid than that in the opposite direction produced by the surface 128. The outward swing of the pins is thus compounded at its termination with a short, bodily movement. The 110 abrupt lateral movement of the ends of the pins, aided by their striking against the wall 50 when the levers ride over ridges, causes the heads of all the buttons carried by the 115 pins to be turned outwardly so that they are located above the receiving groove. Then, as the head 76 descends, the sleeve 118 first moves with it, the ends 112 of the levers remaining in the depression 130. This maintains the outward position of the pins and elevated buttons until the ends of the former are below the top of the wall. Consequently, the buttons are doffed from the pins by contact with said wall. This having 120 125 130

been accomplished, the sleeve strikes the stop-ring 122, and, the movement of the head continuing, the levers 70 ride out of the depressions, straightening the pins, which continue their movement to the normal position.

For the purpose of conveying buttons from the receiving guideway 48 into the raceway 13, there is provided a member revoluble over said guideway and movable into and out of co-operation therewith. Preferably, this member is operable with the elevating pins. To this end, there is formed upon the rod 78 a helix 132, and surrounding this is an internally threaded plate 134. The plate bears upon its upwardly and outwardly inclined periphery 136 a series of groups of bristles or like flexible members 138, the ends of which lie above the guideway. The downward movement of the plate 134 is limited by a vertical sleeve 140 located at the center of the bottom of the container and serving also as a guide for the rod 78. As the elevating pins are raised by the head, the brush member 138 is carried away from the guideway by the cylindrical portion of the rod at the lower end of the helix. But when, in the downward movement of the rod, the plate strikes the upper extremity of the sleeve 140, the helix, traveling through the threaded portion of the plate, causes its rotation. At this time the path of the bristles lies within the guideway, so that they contact with the buttons which have been deposited therein upon the lowering of the pins; and these bristles, revolving in a counter-clockwise direction, as viewed from above, sweep the buttons along the guideway into the raceway 13, which merges tangentially into said guideway. Down the raceway the buttons slide to the controlling mechanism 12.

Having thus described the invention, what is claimed as new and desired to be secured by Letters Patent of the United States is:

1. In a supply apparatus, a container for objects, a conveyor associated with the container, a carrier arranged to engage objects in the container and hold them independently of said container, means for moving the container and carrier relatively to deliver objects from the container and to free them from the carrier, and means movable into engagement with delivered objects to transfer them to the conveyor.

2. In a supplying apparatus, a container for objects, a receiver associated with the container, a raceway leading from the receiver, an object-carrier operating in the container, means for moving the container and carrier relatively to elevate objects from the container, means for moving the carrier in a different direction to deliver the elevated objects to the receiver, and means for removing the objects from the receiver to the raceway.

3. In a supplying apparatus, an object-

container, a receiver associated with the container, an object-carrier entering the container for each carrying operation, means for moving the container and carrier relatively to deliver objects from the container to the receiver, and means for removing the objects from the receiver, there being provision for shifting the object-removing means into and out of co-operation with the receiver.

4. In a supplying apparatus, an object-container, a receiver surrounding the container, an object-carrier operating in the container, means for moving the container and carrier relatively to deliver objects from the container to the receiver, and removing means acting to move objects circumferentially of the receiver.

5. In a supplying apparatus, an object-container, a receiver associated with the container, a raceway leading from the receiver, an object-carrier operating in the container, means for moving the container and carrier relatively to deliver objects from the container to the receiver, and means for changing the positions of objects upon the carrier to points above the receiver in preparation for such delivery.

6. In a supplying apparatus, an object-container, a receiver associated with the container, an object-carrier operating in the container, means for moving the container and carrier relatively to deliver objects from the container to the receiver, and means acting upon the carrier for positioning the objects circumferentially of the carrier for such delivery.

7. In a supplying apparatus, an object-container, a receiver associated with the container, a conveyor leading from the receiver, an object-carrier operating in the container, means for reciprocating the container and carrier relatively to deliver objects from the container to the receiver, and means rotatable under the influence of the relative movement for removing the objects from the receiver to the conveyor.

8. In a supplying apparatus, an object-container, a receiver associated with the container, a raceway leading from the receiver, an object-carrier entering the container, means for moving the container and carrier relatively to deliver objects from the container to the receiver, and means operable under the influence of the relative movement for removing objects from the receiver to the raceway, there also being provision whereby such movement shifts the object-removing means into and out of co-operation with the receiver.

9. In a supplying apparatus, an object-container, a receiver co-operating with a wall of the container for the support of objects, means arranged to vary the relation between the container and receiver and

to hold them in such relation against movement, an object-carrier operating in the container, and means for moving the container and carrier relatively to deliver objects from the container to the receiver.

10. In a supplying apparatus, an object-container, a receiver associated with the container, a raceway leading from the receiver, a carrier arranged to engage an individual object in the container, means for moving the container and carrier relatively to deliver objects from the container to the receiver, and a member movable through the receiver and arranged to deliver objects therefrom to the raceway.

11. In a supplying apparatus, an object-container, a receiver associated with the container, a carrier arranged to engage an individual object in a mass in the container and hold it alone in preparation for delivery, means for moving the container and carrier relatively in one direction to position each object after engagement for delivery to the receiver, and means for moving the container and carrier relatively in another direction to deliver each object held from the carrier to the receiver.

12. In a supplying apparatus, an object-container, a receiver associated with the container, an object-carrier projecting through the bottom of the container, means for moving the carrier to deliver objects from the container to the receiver, and means movable over the receiver to deliver objects therefrom.

13. In a supplying apparatus, an object-container, a receiver associated with the container, a raceway leading from the receiver, an object-carrier projecting through the bottom of the container, means for moving the carrier to deliver objects from the container to the receiver, and means operated by the movement of the carrier to transfer objects from the receiver to the raceway.

14. In a supplying apparatus, a container for objects, means movable to elevate the objects in the container, means operating at the completion of the elevating movement for moving the elevating means in the direction of delivery of the objects from the container to prepare for such delivery, and means for effecting the delivery of the objects thus prepared.

15. In a supplying apparatus, a container for objects, delivering means movable vertically in the container, and means operating at the completion of the vertical movement for moving the delivering means toward the outside of the container, delivery thereafter being effected by further vertical movement of said delivering means.

16. In a supplying apparatus, a container for objects to be operated on, delivering means movable in the container, means for imparting to the delivering means an object-

delivering movement, and means for moving the delivering means to position objects thereon, delivery thereafter being effected by the movement of said delivering means.

17. In a supplying apparatus, a container for objects, delivering means movable vertically in the container, and means for imparting to the delivering means a compound lateral movement at different speeds and for thereafter producing a delivering movement.

18. The combination with an object-container, of a reciprocating head, an object-delivering pin movable by the head through the bottom of the container and being also movable upon said head.

19. The combination with an object-container, of an object-delivering pin movable through the bottom of the container, and means for oscillating the pin at a particular portion only of such movement.

20. The combination with an object-container, of an object-delivering pin movable in the container, and means for swinging the point of the pin toward the outside of the container at the termination only of the delivering movement.

21. The combination with an object-container, of an object-delivering pin movable in the container, and means for swinging the point of the pin in the container, there being an oscillation imparted to the pin in the swinging movement.

22. The combination with an object-container, of an object-delivering pin movable in the container, and means for swinging the point of the pin toward the outside of the container, there being an abrupt oscillation imparted to the pin at the termination of the swinging movement.

23. In a supplying apparatus, a container, delivering means operating in the container, means for reciprocating the delivering means in the container, and means for moving the delivering means laterally in the container during its travel in one direction, said means being arranged to cause a reverse lateral movement beginning only after a portion of the travel in the other direction has occurred.

24. In a supplying apparatus, a container, delivering means operating in the container, means for reciprocating the delivering means vertically in the container, and means for moving the delivering means toward the outside of the container at the completion of its upward movement, said moving means being arranged to cause the movement of the delivering means inwardly after a certain descent thereof.

25. In a supplying apparatus, a container, a delivering pin operating in the container, means for reciprocating the pin vertically in the container, and means for swinging the upper extremity of the pin toward the outside of the container and above its top, said

means being arranged to cause the pin to swing inwardly only when the upper extremity is below the top of the container.

26. The combination with a receptacle for objects, of a guideway surrounding the receptacle, a raceway connected to the guideway, means for elevating objects from the receptacle and depositing them in the guideway, and a revoluble member contacting with the objects in the guideway to move them into the raceway.

27. The combination with a receptacle for objects, of a guideway surrounding the receptacle, a raceway connected to the guideway, means for delivering objects from the receptacle to the guideway, and a flexible member revoluble above the guideway for contact with the objects therein.

28. The combination with a receptacle for objects, of a guideway surrounding the receptacle, a raceway connected to the guideway, means for delivering objects from the receptacle to the guideway, and a member contacting with the objects in the guideway to move them into the raceway, there being provision for moving the member toward and from the guideway.

29. The combination with a cylindrical receptacle for objects to be operated on, of a guideway surrounding the upper portion of the receptacle, an inclined raceway connected to the guideway, means for delivering objects from the receptacle to the guideway, a vertically movable spindle extending through the receptacle, object-delivering means mounted on the spindle, and a member carried by said spindle for contact with the objects in the guideway.

30. The combination with a cylindrical receptacle for objects to be operated on, of a guideway surrounding the upper portion of the receptacle, an inclined raceway connected to the guideway, means for delivering objects from the receptacle to the guideway, a vertically movable spindle extending through the receptacle and having a helical portion, object-delivering means connected to the spindle, and a member arranged to rotate upon the helical portion of the spindle and to contact with objects in the guideway.

31. The combination with a cylindrical receptacle for objects to be operated upon, a guideway surrounding the upper portion of the receptacle, an inclined raceway connected to the guideway, means for delivering objects from the receptacle to the guideway, a vertically movable spindle extending through the receptacle and having a helical portion, object-delivering means connected to the spindle, and a member arranged to rotate upon the helical portion of the spindle for contact with objects in the receiver and to be carried by said spindle during a portion of its movement out of co-operation with the guideway.

32. In a supplying apparatus, a container for objects to be operated upon, a receiver surrounding the container, there being between the container and receiver a wall common to both, means for transferring objects from the container to the receiver, and means arranged to move the container and receiver relatively to vary the effective depth of said receiver.

33. The combination with a button-container, of pins movable in the container and formed to enter button-eyes, means for moving the pins to deliver the buttons from the container, and means for moving said pins to position buttons thereon in preparation for delivery.

34. The combination with a button-container provided in the bottom with openings, of pins movable through the openings and formed to enter button-eyes, and means for moving the pins to produce contact of the buttons with the container.

35. The combination with a button-container provided in the bottom with openings, of pins movable through the openings and formed to enter button-eyes, and means for elevating the pins, moving them toward the outside of the container and lowering said pins to transfer buttons from the container and free them for delivery by their contact with said container.

36. The combination with a button-container provided in the bottom with openings of pins movable through the openings and formed to enter button-eyes, means for elevating the pins, and means traveling with the pins to move them toward the outside of the container.

37. The combination with a button-container provided in the bottom with openings, of a reciprocator head beneath the container, pins pivoted upon the head and projecting through the openings, a cam arranged to act upon the pins to turn them upon their pivots, and a receiver to which the pins deliver.

38. The combination with a button-container provided in the bottom with openings, of a reciprocator head beneath the container, pins pivoted upon the head and projecting through the openings, a cam arranged to act upon the pins to turn them upon their pivots, said cam being movable with the pins, and a receiver to which the pins deliver.

39. The combination with a button-container, of a guideway surrounding the container and arranged to support buttons with the eyes resting upon the edge of said guideway, a raceway communicating with the guideway, and means arranged to enter the button-eyes for transferring buttons from the container to the guideway.

40. The combination with a button-container, of a guideway surrounding the container and arranged to support buttons with

the eyes resting upon the edge of said guideway, means movable over the guideway for carrying buttons therefrom to the raceway, and means arranged to engage the button-

5 eyes for transferring objects from the container to the guideway.

41. The combination with a button-con- tainer having openings in the bottom, of a guideway surrounding the upper portion of

10 the container and arranged to support but- tons with the eyes resting upon the edge of said guideway, and pins movable through the openings in the container and arranged to enter the button-eyes and transfer the but- 15 tons to the guideway.

42. The combination with a button-con- tainer having openings in the bottom, of a guideway surrounding the upper portion of

the container, a raceway communicating with

20 the guideway, a member movable in prox- imity to the container, pins mounted on said member and operating through the con-

tainer-openings to transfer buttons to the guideway, and means movable with the member for carrying the pins from the 25 guideway to the raceway.

43. The combination with a button-con- tainer having openings in the bottom, of a guideway surrounding the upper portion of the container, a raceway communicating 30 with the guideway, a member movable in proximity to the container and having a helical portion, pins mounted on said mem- ber and operating through the container- openings to transfer buttons to the guideway, 35 and a brush rotatable upon the helical portion of the member in contact with the but- tons in the guideway.

In testimony whereof I have signed my name to this specification.

JAMES W. NOURBOURN,
Administrator of the Estate of Albert Latham, Deceased.
